UNITED STATES PATENT OFFICE

125,283

DESIGN FOR A REFRIGERATED STORAGE AND DISPLAY CABINET

Lotus F. Miller, Cambridge City, Ind.

Application November 6, 1940, Serial No. 96,366

Term of patent 14 years

To all whom it may concern:

Be it known that I, Lotus F. Miller, a citizen of the United States, residing at Cambridge City, in the county of Wayne and State of Indiana, have invented a new, original, and ornamental Design for a Refrigerated Storage and Display Cabinet, of which the following is a specification, reference being had to the accompanying drawing, forming part thereof.

In the drawing:

Fig. 1 is a view in perspective of the article,

showing my design, and particularly showing the front or display side of the cabinet;

Fig. 2 is a view similar to Fig. 1 but particularly showing the rear or serving side of the cabinet.

The opposite ends of the cabinet are of substantially the same design.

I claim:

The ornamental design for a refrigerated storage and display cabinet, as shown and described.

LOTUS F. MILLER.
